REISSUED

CARLOS F. JOHANNING, OF DENISON, TEXAS

AUXILIARY BASE AND SWITCH ATTACHMENT FOR TELEPHONES

Application filed October 19, 1929. Serial No. 400,761.

This invention has for its object to provide a new and improved means for the mounting of a plurality of push buttons for use in an electrical circuit to signal persons or departments in proximity to a telephone.

More particularly the invention consists of an auxiliary base to be used in connection with a standard telephone set, and including several push buttons, keys, or other means for connecting the circuit of an electric battery so that individuals remote from the telephone may be summoned.

The invention also aims to provide a base of this character upon which the ordinary standard telephone set is affixed, the whole being symmetrical and neat in appearance, and wherein the electric current for use in the circuit is separate from the telephone circuit.

20 The invention will be better understood from a perusal of the following detailed description, taken in connection with the accompanying drawings, and wherein:

Figure 1 represents a side elevational view 25 in part of a standard telephone of the dial type and illustrating an embodiment of the new and improved base.

Figure 2 is a front elevational view thereof.

30 Figure 3 is a sectional detail view, taken along the line 3—3 of Figure 2, showing the push buttons and wiring; and

Figure 4 is a detail sectional view showing one of the push buttons and connecting parts.

35 Referring more in detail to the drawings, 1 denotes the ordinary base of a standard telephone set, the post being broken away as indicated at 2.

The invention comprises an auxiliary base 3 made of the same character of material as the regular telephone base and being of circular shape except at the point directly in front of the dial 4. At this point the auxiliary base is directed outwardly and formed 40 therein is a recess 4 for the reception of the push buttons 5, mounted in the panel 6, see Figure 3. The panel 6 is secured to the auxiliary base 3 by means of screws 7. Below the push buttons are numerals placed on the 45 insets 8, these numerals indicating as will be

obvious various individuals or departments to be signaled. However, the push buttons may be dispensed with and other means employed to connect and control the circuit. Likewise the numerals may be dispensed with 55 and other characters or names substituted therefor. Also the arrangement is susceptible of other modifications such as substituting a gang push button with one common contact bar.

Below the panel 6 is a contact bar 9 and a spring 10 for returning the button to normal position—common in use. Obviously when the button is depressed the circuit is completed through the spring and contact 60 bar and the current carried along the wires 11 to the battery. The contact bar is properly insulated by the material 12, and the posts 13 support the contact bar from the 65 panel 6.

70 What is claimed as new is:

1. The combination of a desk telephone having a base, an auxiliary base adapted to receive said telephone base and means on said auxiliary base for controlling electrical 75 circuits.

2. The combination of a desk telephone having a base, an auxiliary base adapted to receive said telephone base, and means on said auxiliary base for controlling electrical 80 circuits independent of said telephone.

3. The combination of a desk telephone having a base, an auxiliary base comprising a block upon which said base is adapted to rest and switching means in said block for 85 controlling electrical circuits.

4. The combination of a desk telephone having a base, an auxiliary base comprising a hollow block on which said base is adapted to rest and be fastened, switching means in 90 said block for controlling electrical circuits and identification means for said switching means mounted adjacent thereto on said block.

5. The combination of a desk telephone 95 having a base and an auxiliary base comprising a block upon which said base is adapted to rest, a panel mounted in said block and switching means mounted on said panel.

6. The combination of a desk telephone having a base, an auxiliary base and support adapted to receive said telephone base, said auxiliary base being hollow at least in the part extending in front of the telephone and electrical switches mounted on said part and extending into said hollow part.

In testimony whereof I affix my signature.
CARLOS F. JOHANNING.
